EXPANDING BRACELET

Filed Jan. 31, 1923

UNITED STATES PATENT OFFICE.

FRANK JONES AND ERNEST JONES, OF BIRMINGHAM, ENGLAND.

EXPANDING BRACELET.

Application filed January 31, 1923, Serial No. 616,146, and in Great Britain February 3, 1922.

This invention has reference to expanding bracelets of the type in which a series of pairs of side-plates or side-links are connected at their ends by cross-pins that pass transversely through and are slidable within side-slotted centre links; each centre-link containing two spiral springs disposed end to end, or in alignment with one another, and each having a fixed abutment on a closed end of the centre-link and a sliding abutment on the cross pin of a complementary pair of side plates, so that whilst the expanding thrust of the springs normally tends to draw the side plates together endwise and so maintain the bracelet in its contracted condition, the application of end-wise pull to the chain will compress the springs between their respective stationary and sliding abutments and longitudinally displace the side plates relatively to the spring-containing centre-links for expanding the bracelet.

In bracelets of this type as ordinarily constructed, straight wire pins are used to join up the ends of the side plates and serve as abutments for the springs contained in the centre-links, and as these pins have of necessity to be connected to the side plates a distance inwards of the extremities of the latter, the expansion capacity of the bracelet is consequently limited.

According to our present invention, we preferably use as the movable abutments for the pair of springs in each centre-link, cross-pins or slides of the cranked type and dispose the cranks toward one another so that the spring-abutment parts thereof may come together back-to-back in the fully-contracted condition of the bracelet, and to maintain the springs in proper relation to their abutments on the center link ends and on the cross-slides, we mount the two springs of each centre link on a fixed longitudinal guide wire that passes through central holes or clearances in the said slides (the sole function of these wires being to correctly locate the springs in relation to their moving and fixed abutments). While the use of the guide wire is preferred, it is to be understood that the same may be omitted without departing from the scope of our invention, as we find that the other features of our invention combine to produce a highly satisfactory expanding bracelet even without the use of the fixed guide wire. To eliminate friction between the said slides and the spring guides and en-

sure smooth and easy expansion and contraction of the bracelet, we make the guide-wire clearances in the slides of an area larger than the section of the wire and we prevent twisting or angular displacement of the slides (such as might cause the said slides to bind on the wires and also deform or distort the springs in a manner that might cause the latter likewise to bind on the wires) by using the center link side-slots as guides for the slides, or by interconnecting the slides with the said side-slots in such a manner that the said slides cannot twist or rock inside the links, the only relative movement possible between the slides and the links is of a sliding nature. This interconnection of the slides with the centre links further enables the outer extremities of the former to be used as non-rotatable pivots for the side-plates to give the desired circumferential flexibility to the bracelet.

The application of our invention to expanding bracelet chain is shown in the accompanying drawings, in which—

Figure 1 is an elevation of a length of the said chain.

Figure 2 is a sectional plan showing the parts in the positions they respectively assume when the chain is contracted.

Figure 3 is a similar sectional plan showing the chain expanded to the maximum extent.

Figure 4 is a view in which one of the centre-links is shown in longitudinal section on the section line 4—4, Figure 3, and the complementary side-plates are shown in elevation.

Figure 5 shows one of the centre-links in side elevation the slides being drawn in section to illustrate how the side-webs of the said slides engage the slots of the link to prevent relative twisting or angular movement between the slides and the link.

Figure 6 is a section of Figure 4 on the section line 6—6.

Figure 7 shows one of the slides in elevation, plan and side view, and

Figure 8 is an elevation and a longitudinal section of one of the side plates.

The same letters of reference indicate corresponding parts in the several figures.

In the chain shown in the said drawing, *a* are the side-slotted centre-links and *b'*, *b²*, are the pairs of side-plates: *c'*, *c²* are the spring-abutment slides that are displaceable

longitudinally relatively to the centre-link, and to the outer extremities of which the side-plates are pivoted, whilst d' , d'' , are the compressible springs which are interposed 5 respectively between the said slides and the closed ends of the centre link as illustrated in Figures 2 and 3.

According to our said invention, the slides c' , c'' , are cranked in opposite directions substantially as shown so as to dispose their mid-10 die or spring abutment portions d^3 inwards of the side-plate pivots d^4 ; the extent of this cranking (in the illustrated construction) being such that, when the chain is fully 15 contracted, as shown in Figure 2, the portions d^3 of the two slides abut or come together back to back in substantially the same plane as the meeting extremities of the side-plates that are connected to the said 20 slides—this plan being indicated by the dotted line x' in the said Figure 2.

In this way the lengths of the two spring-accommodation spaces available inside each 25 centre-link are increased to extents corresponding to the crankings of the slides, thus permitting of the use of correspondingly longer springs and augmenting the total extensibility of the bracelet, whilst the arrangement also ensures that the spring system can 30 draw the ends of the adjacent pairs of side plates close together or into actual contact in the fully-contracted condition of the chain.

The middle or spring-bearing portions d^3 35 of the slides are preferably of a shape as will afford an adequate surface for its spring to thrust against, whilst to maintain the springs in correct relation to the said abutments d^3 , a longitudinal guide-wire or runner e is 40 fixed between the opposite ends of the centre link and holes or clearances f are pierced in the centres of the slide-abutments for the accommodation of this stationary guide-wire; the areas of these clearances being 45 larger than the section of the wires (see Figure 6) so as to avoid friction between these parts.

To prevent twisting or rotational displacement of the slides such as might cause them 50 to rub or bend on the guide-wires and also bring about spring distortion tending to set up friction or binding of the springs on the wires, the slides are keyed to the centre-links by means of the side portions g of the cranks (i. e. by the parts of the cranks that extend 55 from the spring-bearing portions to the side plate pivots); these sides g being made of a depth or section only a little less than the depth of the centre-link side-slots h , and in 60 assembling the parts, the said crank-sides are made to fit or engage within the corresponding slots (see Figures 5 and 6) in such a way that whilst the slides can move freely in the lengthwise direction of the centre-link, they

are incapable of rotational or angular movement relatively thereto. 65

The extremities of the key-line sides of each slide are bent outwardly and arranged to project laterally beyond the opposite sides of the centre-link and constitute the side-plate pivots; these bent-out ends being formed with small heads or enlargements whereto the ends of the complementary side-plates may so be pivoted or connected to the 70 slides that when the bracket is in use, the side plates can hinge or work on the said pivots when the chain is flexed circumferentially without transmitting any spring-distorting movement to the slides. 75

The assembly of the side plates to the slide-pivots may be provided for by forming in the middles of the inner sides of the said plates, gates j large enough to pass over the pivot heads and providing longitudinal slots j' extending from the gate towards the 80 ends of the links, as shown in Figure 4, along which the pivot-necks of the slides are drawn after the heads of such pivots have 85 been passed through the gate.

Any other method may, however, be adopted 90 for connecting the side-plates to the slides so long as provision is made for the pivoting or angular movement of the said plates relatively to the centre-links.

Having described our invention, what we 95 claim and desire to secure by Letters Patent is:—

An expanding bracelet comprising interconnected pairs of side plates and center links, the center links being interposed between the members of adjacent pairs of side plates, cranked spring abutment slides having portions slidably interfitted with the side plates, said side plates and said spring abutment slides having cooperating guide means to hold the slides against twisting and constrain them to proper movement, said slides having spring abutment portions located within the center links and connecting portions between the abutment portions and the guide means of the slides, said center links having slots accommodating the connecting portions, springs abutting the abutment portions of the slides and the ends of the center links, and a fixed guide wire extending axially through each center link and through the springs therein, said abutment portions having openings larger than the wires and through which the wires extend loosely whereby the guide wires serve solely for the purpose of locating and maintaining the springs in correct relationship to their abutments. 110

In testimony whereof they hereunto affix their signatures.

FRANK JONES.
ERNEST JONES.
